UNITED STATES PATENT OFFICE.

CARL LOUIS STERN AND ARTHUR VICTOR BUGLER, OF LONDON, ENGLAND, ASSIGNORS TO LINOTYPE AND MACHINERY LIMITED, OF LONDON, ENGLAND, A BRITISH COMPANY.

SHEET FEEDING AND DELIVERING MECHANISM FOR PRINTING MACHINES.

Original application filed July 7, 1922, Serial No. 573,277, and in Great Britain July 18, 1921.

Divided and this application filed January 13, 1927. Serial No. 160,789.

This invention relates to sheet feeding and delivering mechanism for printing machines, such as that described in application for Letters Patent Serial No. 573,277, filed 5 7th July, 1922, from which the present application has been divided, and particularly to those constructions known as pile feeders and pile deliveries. For convenience the application Serial No. 573,277 is herein referred to as the original application. In 10 producing, with such mechanism, multi-colour work, that is to say, printing in two or more colours on one side of each sheet, it is usual, after the sheets have received 15 their first impression, to transfer them by hand in batches from the delivery pile back to the feeding pile, from which they are again fed into the machine, with the same edge leading as in the previous printing, 20 for receiving the second impression, and so on for any further impressions. In producing with this type of mechanism, perfecto work, that is to say, sheets printed on both sides, it is necessary, in effecting a 25 transfer similar to that above mentioned, to invert each batch of sheets, and also reverse the same so that the edge which was the leading one during the printing on one side shall be the leading edge during the printing 30 on the opposite side.

In both the above named systems of working, the handling of the sheets during the transfer from the delivery mechanism to the feed mechanism disturbs the pile alignment 35 which had been previously secured by the jogging mechanism on the delivery board, and such alignment has to be restored before the sheets are again fed through the machine to ensure proper register of the successive impressions.

The object of the present invention is to provide means whereby the transfer from the delivery mechanism to the feeding mechanism may be effected without necessitating 45 under any circumstances, an inversion of the sheets and disturbance of the pile alignment of such sheets.

For attaining the above named object, new or improved means are provided in conjunction with the feed board whereby the top sheet may be fed from the pile with either its front or its rear edge leading, and

when fed with its rear edge leading, inverted.

The invention will now be described by 55 reference to the accompanying drawings in which:—

Figure 1 is a diagrammatic side elevation of the feed end of a printing machine provided with the improved feeding mechanism; 60

Figure 2 is a side elevation of a feeder head embodying the present improvements, and

Figure 3 is an elevation as viewed from 65 the right-hand side of Figure 2, and with the central portion broken away.

The application of the invention to the feed end of a printing machine is illustrated 70 diagrammatically in Figure 1, a single reversible feeder head 2 being there shown towards the left hand side in the position for operating near the foremost edge of the pile 4 on the feed board 1 to lift the top sheets from the pile in succession and introduce them between the feed rolls 5, by which they are passed along the tapes 6 to the rolls 7, which in turn pass them on to the printing couple. The position occupied by the same feeder head towards the right in Figure 1 and there marked 3, is that in which it operates near the rear edge of the pile 4 to lift the top sheets from the pile in 75 succession and deliver them between the rolls 8 to the endless tape 9, by which they are inverted over the roll 10, and thence fed by sheet-conveying devices such as the tapes 11, 12, 13 to the rolls 7, by which they are delivered to the printing couple, as in the case of sheets fed direct from the foremost 80 edge of the pile.

The head comprises two side frames 3, 3 (which numeral is herein used to designate the head when referred to as a whole), upon which are mounted the shafts for supporting and operating the sheet lifting and separating devices, these frames being supported above the level of the pile 4 on side rails 18, 18, along which the head is adjustable as a whole by means of racks 23 at the side of the rails 18 and pinions 19, one at each end of a shaft 22 which is rotated when desired by means of gear wheels 20 on a shaft 84 95 extending axially through a tubular shaft 21,

The sheet lifting device, which in the constructional form shown is pneumatic, is carried by, and adjustable transversely along, a shaft 24, and is operated from a rotating shaft 25, which is driven by means of a spiral gear 27 adjustable along the first-driven shaft 26. The shaft 24 is journalled in bearings 28 sliding in guides 29 in the side frames and is vertically reciprocated by means of grooved cams 30 on the shaft 25, which are engaged by bowls 31 on the bearings 28.

The suction device 32, by which the top sheets are lifted from the pile, is adjustable vertically, by means of milled nuts 83, within a hollow casing 82 which is pivoted at 33 to a forked bracket 34 carried by a rod 35 capable of sliding fore-and-aft in a bearing bracket 36 which is adjustable along the shaft 24. The bracket 34 is connected by a link 37 to an arm 81 fast on shaft 71 which is rocked through segmental gear 72, on the lower end of an arm 73, by a grooved cam 42, mounted on the shaft 25, with which engages a bowl 43 on said arm 73.

The sheet lifter 32 is thus, through the vertical movement of the shaft 24, periodically lowered on to and raised away from the pile 4, and, through the rocking of the shaft 71, moved backwards and forwards above the pile. At appropriate stages during these movements, a pipe 44, carried by the frames 3, with which pipe the lifter 32 communicates through a flexible tube 45, is connected to an air-exhauster and opened to atmosphere, so that the successive top sheets of the pile are lifted, fed forward and released. There are preferably two sheets feeding devices operating simultaneously on each head, and these are located at such distance apart on the shaft 24 as to act near opposite sides of the pile.

The lifter 32 is designed to perform, at the leading edge of the pile, the functions of both lifter and separator, and in its last-named function it is assisted by an air blast projected against the said leading edge through apertures in one or other of two pipes located near opposite ends of the pile in such positions between the rails 18 that either one or the other can be employed according to the position of the leading edge, although in the drawing there is shown only one such pipe 89 with its apertures 90 which will be in use when feeding direct, i. e., towards the left of Figures 1 and 2.

The mechanism for imparting the required motions to the lifter 32 is arranged so that the lifter may be operated reversely at opposite sides of the feeder head. For this purpose there is provided a second rocking shaft 21 which is rocked through a segmental gear 80 and lever arm 78. the lever arm 78 is pivoted to the respective frame 3 at 79 and is provided with a second arm 79^a carry-

ing a toothed sector 77 meshing with a similar sector 76 on an arm 75 fast to the before described arm 73.

The sheet-separating action of the lifter, in addition to being assisted by the air blast above referred to, is further assisted by the buckling of the top sheet at the commencement of the lifting action. The lifter therefore has imparted to it a tilting motion about the axis of the studs 33. The cam 42 is so shaped that the initial motion given by it to the lifter 32 is backwards, i. e., away from the leading edge of the pile, and the lifter 32, at a point above the pivot 33, contacts with one end of a rod 86 which is adjustably supported at its opposite end in an upward extension 87 of the bracket 36, and is provided with a lock nut 88 bearing against said extension 87, by which means the rearward movement of the upper part of the lifter is restricted and its sheet-engaging end consequently is tilted upwardly and rearwardly. On its subsequent forward motion the lifter is restored to its normal vertical position by the spring 63.

It will now be understood that by the respective movements of the shafts 24 and 71, the desired sheet separating and feeding motions of the lifter 32 will be secured.

When sheets are to be fed from the opposite edge of the pile as might be required when feeding to inverting mechanism for perfecter work, as in the original application, the head is racked along the rails 18, by turning the shaft 84, to the proper position for operating on the rearward edge of the pile and the lifter reversed. The last-named reversal is effected by disconnecting the link 37 from arm 81 and bracket 34 and removing the latter as well as the lifter 32, and rods 35 and 86 to the opposite side of the head, inserting the rod 35 into that end of the bracket 36 and the rod 86 into the extension 87^a, at the same time removing the pipe 44 from the bearing 91 to the bearing 92. When in this position, and with the link 37 connected to bracket 34 and arm 38, the lifter will receive from the shafts 24 and 21 a motion the reverse of that just previously described, so that the sheets will be fed in the reverse direction from the opposite or rearward edge of the pile. Although only one lifter 32 has been referred to, obviously two or more may be arranged on the shaft 24, adjustable thereon transversely of the pile for different sizes of sheets, with appropriate arms on the rocking shafts 21 and 71, to operate simultaneously on different parts of the pile.

Having described our invention, we declare that what we claim and desire to secure by Letters Patent is:—

1. In or for a printing machine, sheet feeding mechanism comprising in combination a feeder head, a sheet lifter supported

in the feeder head, means in the feeder head adapted to support the lifter alternatively at the front or back of said feeder head, and mechanism carried by the feeder head 5 operative to reciprocate the lifter in planes at an angle to each other in either of its positions in the feeder head.

2. In or for a printing machine, sheet feeding mechanism comprising in combination 10 a feeder head, means adapted to adjust the feeder head from one to the other end of the pile from which the sheets are to be fed, a sheet lifter supported in the feeder head, means in the feeder head adapted to 15 support the lifter alternatively at the front or back of said feeder head, and mechanism carried by the feeder head operative to reciprocate the lifter in planes at an angle to each other in either of its positions in the 20 feeder head.

3. In or for a printing machine, sheet feeding means comprising in combination a feeder head, a horizontal shaft vertically 25 movable in guides in the feeder head, a bracket adjustable along the horizontal shaft, a sheet lifter supported in the bracket with a capacity for moving in fore-and-aft direction, means operative to vertically reciprocate the horizontal shaft, means in the 30 feeder head adapted to support the lifter alternatively at the front or back of the feeder head, and means operative to horizontally reciprocate the lifter relatively to the bracket whether it be situated at the 35 front or back of the feeder head.

4. In or for a printing machine, sheet feeding means comprising in combination a feeder head, a horizontal shaft vertically 40 movable in guides in the feeder head, a bracket adjustable along the horizontal shaft, a forked bracket supported by the first named bracket with a capacity for mov-

ing relatively thereto in fore-and-aft direction, a sheet lifter pivotally supported in the forked bracket, means operative to vertically reciprocate the horizontal shaft, means in the feeder head adapted to support the lifter alternatively at the front or back of the feeder head, means operative to horizontally reciprocate the forked bracket and 45 lifter relatively to the first named bracket whether it be situated at the front or back of the feeder head, and means adapted to arrest this horizontal movement of the lifter at one side of the pivots of said lifter. 50 55

5. In or for a printing machine, sheet feeding means comprising in combination a feeder head, a horizontal shaft vertically movable in guides in the feeder head, a bracket adjustable along the horizontal 60 shaft, a forked bracket supported by the first named bracket with a capacity for moving relatively thereto in fore-and-aft direction, a sheet lifter pivotally supported in the forked bracket, means operative to vertically reciprocate the horizontal shaft means in the feeder head adapted to support the lifter alternatively at the front or back of the feeder head, means operative to horizontally reciprocate the forked bracket and 65 70 lifter relatively to the first named bracket whether it be situated at the front or back of the feeder head, and means adapted to arrest this horizontal movement of the lifter at one side of the pivots of said lifter, said 75 last named means being mounted in the feeder head with a capacity for reversal to correspond with the fore-and-aft positions of the lifter in said head.

In testimony whereof we have affixed our 80 signatures hereto.

CARL LOUIS STERN.
ARTHUR VICTOR BUGLER.
